UNITED STATES PATENT OFFICE.

LIPA POLINKOWSKY, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 17, 1919. Serial No. 338,441.

To all whom it may concern:

Be it known that I, LIPA POLINKOWSKY, a citizen of Russia, residing at Antwerp, Belgium, have invented certain new and useful 5 Improvements in Telephone-Exchange Systems, of which the following is a full, clear, concise, and exact description.

This invention relates to telephone exchange systems and more especially to systems 10 wherein talking connections between subscribers' lines are established by means of machine switching apparatus.

In system of the character to which the present invention is particularly applicable, 15 the selective switches, which serve to set up connections between subscribers' lines, are arranged to be controlled by register senders. Upon the initiation of a call on a subscriber's line, an idle sender is automatically associated with such line and the calling subscriber proceeds to register the designation 20 of the desired line on the sender taken for use. After the register sender has been positioned, it is then operative to control the switches in accordance with the required 25 selections.

The object of the invention is the provision of an arrangement wherein, if a register sender fails to function properly or if 30 a calling subscriber is unable to control the setting thereof, said sender is automatically associated with an operator's position.

A feature of the invention resides in the provision of switching means common to a 35 plurality of register senders and arranged to associate any one of such senders that does not function properly with an operator's position.

Another feature is the provision of a common switching means for a plurality of register senders so arranged that, when any register sender is taken for use and the registration of the designation thereon is delayed 40 for a predetermined interval, said switching means automatically associates such sender with an operator's position.

A further feature of the invention relates 45 to a signal arrangement at the operator's position, operated in accordance with the operation of said switching means to identify to the operator the designation of the register sender that has failed to progress in its regular operation.

Other features contemplated by this invention will become apparent from the following description and the appended claims. 55

In the drawings Figs. 1 to 3 taken in order from left to right, illustrate so much of a telephone exchange system as is necessary to an understanding of the invention. 60

Fig. 1 shows a subscriber's line and also illustrates diagrammatically a first line finder switch and a second line finder switch for extending said line to the circuits of a first group selector in the exchange. To the right 65 of the broken line in Fig. 1 there is shown the detailed circuits of a hunting switch which has access to a plurality of register senders together with a schematic illustration of the arrangement on the terminal 70 bank of such hunting switch. To the left of the broken line in Fig. 1 is shown an operator's position in a distant exchange and a trunk circuit leading from the operator's position to said hunting switch. 75

Figs. 2 and 3 show the detailed circuits of a register sender for controlling the operation of the group and final selector switches. Within the broken lines at the upper left-hand corner of Fig. 2 a portion of 80 a second register sender is shown and also the manner in which the several register senders appear in the terminal bank of the hunting switch shown in Fig. 1. Figs. 2 and 3 further show the brushes and the talking 85 circuit of a first group selector switch and means for associating a register sender with such switch when a calling line is extended thereto. Fig. 4 is a schematic illustration of one of the register senders together with a 90 sender switch for associating the sender with the selector switch.

In machine switching telephone systems of the full automatic type employing selective switches operated in accordance with 95 the reverte impulse control principle, register sending mechanisms are provided in the exchange for controlling the selective operations of such switches. Following the initiation of a call an idle one of these register senders is automatically connected to the calling subscriber's line ready to be set up by impulses transmitted from the calling substation in accordance with the designation of the desired line. It may happen 100 that, upon an idle register sender being as-

sociated with a calling line, such sender fails to operate properly in response to the transmission of impulses from the calling substation. Furthermore, while the calling subscriber is able to initiate a call and appropriate for his use a register sender, he may be unable to proceed with the setting-up of such sender due to a defective impulse transmitter or for other reasons. It is, therefore, desirable in the event of unstandard conditions of this nature that an operator's attention be called to the fact that a calling subscriber has initiated a call but is unable to proceed with the setting up of the register sender. Where the exchange or the satellite in the system is of small capacity the installation and maintenance of a trouble operator's position in each of such small exchanges is not warranted. Accordingly, as is contemplated by the present invention, the trouble operator's position is located in a central exchange and trunk lines are provided leading from the operator's position to the smaller exchanges and satellites. Each of these trunk lines incoming from the operator's position in the central exchange terminates in a hunting switch which is arranged to select automatically any one of a plurality of register senders in which the unstandard condition exists. These hunting switches are so designed that if a call is initiated and the setting-up of the appropriated sender is not proceeded within a predetermined interval of time, the hunting switch automatically selects such sender and associates it with the operator's position in the distant exchange. Moreover, a talking connection is established between the calling subscriber's line and the trouble operator's position in order that the subscriber may inform the operator of the designation of the line with which he desires to obtain connection. If the trouble is due to the subscriber's inability to transmit impulses to the exchange, the operator, who is also provided with an impulse sender, is enabled to set-up the sender in accordance with the required designation and the call proceeds thereafter in the usual manner. If the sender has failed to function, the operator, who is given a visual signal indicating the designation of the particular sender concerned, informs a trouble man of this fact who is then enabled to immediately locate and correct the unstandard condition.

The register sender shown in detail in Figs. 2 and 3 appears in the hunting switch in terminals 226, 227, 228 and 229. These terminals are shown as the 5th set, counting from the left in the upper row in the schematic arrangement shown in Fig. 1. The second register sender, a portion of which is shown in Fig. 2, appears in the hunting switch in terminals 235, 236, 237 and 238,

or the 9th set in the upper row in Fig. 1. The remaining register senders to which the hunting switch has access appear in like manner in the terminal bank of such switch. The lowermost terminal 239 of the first set, 70 which indicates the nominal position of the hunting switch, is connected to ground. When the switch is taken for use the brush 129, after leaving its normal position, first engages the terminal 240 in the third set. After the hunting switch passes over terminals 226, 227, 228 and 229 individual to the first register sender, the brush 129 engages a terminal 241 similar to the terminal 240. After having passed the terminals 235, 236, 237 and 238 individual to the second sender, the brush 129 next engages a terminal 248 and so on. The purpose of the terminals 240, 241, 248, etc., which are placed in advance of the terminal sets representing 80 the successive register senders, will be more fully explained hereinafter. 85

A plurality of sequence switches of the well-known construction is shown in the disclosure of this application for performing the various circuit-controlling operations. Where more than one sequence switch appears on the same sheet of the drawings, each such sequence switch and the contacts controlled thereby are located within the same area bounded by broken lines. 90

A description in detail will now be given of the operation of the system when a call is extended from one subscriber's line to another. Assume the subscriber at the substation 100 wishes to obtain a connection with a subscriber's line, the substation of which is shown at 300. The calling subscriber upon removing his receiver from the switchhook initiates in the usual manner the operation of a first line finder switch 101 and a second line finder switch 102 which extend the calling line over conductors 103, 104 to the circuits of a first group selector switch, the brushes of which are illustrated at 306 and 307. The call having been extended to the first group selector, certain circuit changes are brought about thereat and a sender selector switch is started in operation to select an idle 105 register sender and connect the same to the calling subscriber's line. Referring to Fig. 4 the sender selector switch is shown in the form of a sequence switch 401 having contacts 402, 403, 404 and 405. The sender 110 400 illustrated schematically is associable through the contacts of the sender selector switch 401 with the circuit 406 leading to the selector switch whose brushes 407 and 408 are shown. The leads from the sender 400 are multiplied to appear in corresponding contacts of other sender selector switches as illustrated. Assuming that the register sender shown in Figs. 2 and 3 is the one 115 taken for use, this register sender is then 120 125 130

connected over leads 202, 203, 301, 302, 303 to the circuits of the first group selector switch. For a complete disclosure and description of the manner in which a register 5 sender of this type is associated by a sender selector with the first group selector circuits, reference is made to the patent to Polinkowsky No. 1,365,269, issued January 11, 1921. The first and second line finder 10 switches 101 and 102 and the group selector switch 306, 307, shown diagrammatically in the present disclosure, may also be of the same type as the corresponding switches shown in the above application.

15 At the time of the seizure of the register sender by the sender selector, relay 208 is energized by means of a circuit closed from battery through its left-hand winding, contact 212 (1), and conductor 303 to ground 20 at the first group selector. The manner in which this ground is placed upon the conductor 303 is fully explained in the above-mentioned application. Relay 208 closes a 25 circuit through its right-hand winding for driving sequence switch 220 into position 3. On leaving position 2 sequence switch 220 opens at its contact 212 the circuit of the left-hand winding of relay 208 and the right-hand winding of relay 208 being 30 shunted by the master contact 224 between positions 1 and 3 of sequence switch 220, relay 208 deenergizes. Sequence switch 220, therefore, comes to rest in position 3. A circuit is now closed from battery 35 through the contact 214 (3), winding of relay 206, to ground, at the back contact and armature of relay 208. Also in position 3 of sequence switch 220 the primary winding of the dialing tone coil 241 is closed in series 40 with the interrupter 242 at the contact 243. A characteristic tone is thereby transmitted over the conductors 202, 203 and 103 and 104 to the receiver at the calling subscriber's station. The circuit over which 45 this dialing tone is sent to the substation and which constitutes the impulse circuit for controlling the setting of the register sender, is closed at this time by sequence switch contacts 200 and 201 belonging to the 50 controlling sequence switch (not shown) of the group selector. In position 3 of sequence switch 220 the stepping relay 225 energizes in series with the calling line and closes a circuit from ground over the armature and front contact of relay 225, armature 55 and front contact of relay 206, contact 244 (3), right-hand winding and armature and contact of relay 207, contact 209 (3), winding of the tens thousands register 60 400 to battery and ground. At the same time a parallel circuit is closed through the left-hand winding of relay 207 to ground at the armature and front contact of relay 225. The relay 207 is differential in its winding 65 so that when both of the above-traced circuits are closed at the same time this relay does not attract its armature. The register 400, however, energizes and moves out of position 0. Between position 0 and position 1 the master contact 403 of register 400 closes a shunt circuit around the right-hand winding of relay 407. This relay, therefore, energizes over its left-hand winding and attracts its armature. The register 400 continues under the control of 70 its master contact into position 1. The calling subscriber hearing the characteristic tone in his receiver manipulates his impulse transmitter 133 to send the first series of impulses to the register sender. 80 On the first interruption of the line circuit, the stepping relay 225 deenergizes and opens the circuit of the left-hand winding of relay 207, permitting this latter relay to release its armature. On the next closure 85 of the line circuit and the consequent operation of relay 225, the above-traced circuit is closed for the register 400. Register 400 advances from position 1 into position 2 and differential relay 207 is again energized. 90 This method of operation continues, the tens thousands register 400 advancing through one position for each interruption of the line circuit during the transmission of the 95 first series of impulses. The calling subscriber's impulse transmitter 133 is so constructed that the last interruption of the line in each series is of comparatively longer duration than the preceding interruptions. Hence on the last interruption the relay 225 100 maintains its armature retracted for a comparatively longer interval than on the preceding retractions. The circuit which leads from battery through the windings of relay 205, contact 213 (3), to ground at the back 105 contact and armature of relay 225 is therefore closed for a time sufficient to permit the energization of relay 205. Relay 205 is of the slow-to-energize type and does not operate in response to short closures of its 110 circuit. The relay 205 closes a circuit for relay 208 which in turn completes a circuit through its right-hand winding, as above described, for driving sequence switch 220 out of position 3 and into position 5. Relay 115 205 deenergizes as soon as sequence switch 220 opens its contact 213 and moves into position 3 and the calling line is closed at the substation to energize relay 225 before contact 213 is again closed in position 5. Therefore, relay 205 remains deenergized and sequence 220 stops when it reaches position 5. In moving from position 3 into position 5 sequence switch 220 at its contact 120 209 shifts the control of the stepping relay 225 from the tens thousands register 400 to the thousands register 500. A circuit is now completed from ground over the armature and front contact of relay 225, armature and front contact of 125 130

- relay 206, contact 402 of register 400, right-hand winding and armature and contact of relay 207, contact 209 (5), winding of register 500 to battery and ground. Relay 207 does not operate since both of its windings are energized. The thousands register 500, however, advances from position 0 into position 1. When passing from position 0 to position 1, the master contact of this 10 register shunts the right-hand winding of relay 207 and said relay attracts its armature. When the calling subscriber operates his dial for the second series of impulses, the stepping relay 225 deenergizes at each 15 interruption of the line. Relay 207 on the first interruption of the line deenergizes, and upon the next attraction of the armature of relay 225, the thousands register 500 is advanced from position 1 into position 2. In this manner the thousands register is 20 driven to a position corresponding to the number of impulses sent in the second series. At the end of the second series of impulses the slow-to-energize relay 225 is operated 25 and closes the circuit of relay 208. Relay 208 closes the circuit for driving sequence switch 220 out of position 5 and into position 8.
- In position 8 of sequence switch 220 the 30 hundreds register 600 is placed under the control of the stepping relay 225. The circuit for operating the register 600 may be traced from ground over the armature and front contact of relay 225, armature and front contact of relay 206, contact 402, right-hand winding and armature and contact of relay 207, contact 210 (8), winding of the hundreds register 600 to battery and ground. In the same manner as described 35 in connection with the first two registers 400 and 500, the hundreds register 600 is driven step-by-step under the control of the stepping relay 225, until it reaches a position corresponding to the number of impulses 40 in the third series. At the last comparatively long impulse of this series, the slow-to-energize relay 205 attracts its armatures and the sequence switch 220 is driven from 45 position 8 into position 10.
- In position 10 of sequence switch 220 a 50 circuit is completed from ground to the armature and front contact of relay 225, armature and front contact of relay 206, contact 402, right-hand winding and armature and contact of relay 207, contact 210 (10), winding of the tens register 700 to battery and ground. For each impulse transmitted in the tens series the register 700 is moved forward one position. At the 55 last interruption of the line in the tens series the slow-to-energize relay 205 attracts its armature and closes a circuit for relay 208 which in turn completes a circuit for driving sequence switch 220 out of position 60 10 and into position 12. In this position the following circuit is closed for the units register 800: ground, over the armature and front contact of relay 225, armature and front contact of relay 206, contact 402, right-hand winding and armature and contact of relay 207, contact 211 (12), winding of the units register 800, to battery and ground. The calling subscriber now sends the final 65 series of impulses and the units register is set up to a position corresponding to the 70 number of interruptions produced in the line during the transmission of this series. At the last interruption of the line circuit the relay 205 is again energized and sequence switch 220 advances from position 12 into 75 position 14. On reaching position 14 the sequence switch 220 is immediately driven into position 15 as soon as relay 225 becomes deenergized by means of the following circuit: battery, through the winding of sequence switch 220 contact 215 (14), back contact and armature of relay 225 to ground. The relay 225 is deenergized at this time in 80 a manner to be explained hereinafter.
- When the calling subscriber has completed 85 the setting of the first two registers, at which time the sequence switch 220 moves from position 5 into position 8, the first group selecting operation is proceeded with, without waiting for the remaining registers to 90 be positioned. As sequence switch 220 reaches position 6 it closes the following circuit to drive sequence switch 310 out of position 1 and into position 3: battery, through the winding of sequence switch 310, contact 95 311 (1), contact and right-hand armature of relay 312, contact 401 of register 400 to ground at contact 245 of sequence switch 220. In position 3 of sequence switch 310 100 the fundamental circuit for controlling the brush selection at the first group selector is closed. This circuit may be traced from ground over contact 313 (3), contact and armature of relay 314, winding of the stepping relay 315, contact 316 (3), over the conductor 301 to the usual control relay (not shown), at the first group selector. It is not thought necessary to give a complete 105 description of the operation of the register sender in its control of the group and final selector switches. It is sufficient to observe 110 that each of the several registers 400, 500, 600, 700 and 800 is driven back to its normal position from the position to which it was set by the calling subscriber to control 115 the successive selective operations in the extension of the call through to the called subscriber's line 300. This register sender is of the same type and operates in the same manner as the register sender shown in the 120 above-mentioned patent No. 1,365,269, issued January 11, 1921. It may be noted that while sequence switch 310 is passing from position 12 to position 15 it closes the following 125 circuit for energizing relay 249: 130

- ground, contact 323 (2+14), left-hand armature and back contact of relay 330, contact 331 (13), thence through the winding of relay 249 to battery. Relay 249 operates 5 and at its right back contact opens the circuit of relay 225. Relay 225 releases and closes the circuit hereinbefore traced for driving sequence switch 220 out of position 14.
- 10 After the switches have been set up and the connection established to the called line the holding circuit of the stepping relay 225 is opened at contacts 200 and 201 by the advance, in the usual manner, of the sequence switch controlling the circuits of the first group selector. At the same time the registers 400, 500, 600, 700 and 800 having all been restored to their normal positions, the sequence switch 310 is driven into position 15. In position 15 of sequence switch 310 a circuit is closed from battery through the winding of sequence switch 310, contact 317 (15), contact 404 (0), contact 501 (0), contact 318 (15), contact 319 (15), contact 601 (0), contact 320 (15), to ground at contact 246 (15). Sequence switch 310 moves out of position 15 and into position 16 where a circuit is closed from ground through the winding of sequence switch 310, contact 311 (16), contact 701 (0), contact 321 (16), to ground at contact 246 (15). Sequence switch 310 is driven from position 16 into position 17 where a circuit is closed from battery through the winding of sequence switch 310, contact 311 (17), contact 801 (0), back contact and armature of relay 322, contact 802 (0), contact 321 (17), to ground at contact 246 (15). Sequence switch 310, therefore, moves from position 17 into position 1. In position 1 of sequence switch 310 a circuit is completed from battery through the left-hand winding of relay 208, contact 212 (15), contact 323 (1), to ground. Relay 208 energizes and completes a circuit for driving sequence switch 320 into position 17. In position 17 relay 205 is energized by means of a circuit including contact 213 (17), back contact and armature of relay 206, and contact 216 (17).
- 50 Relay 205 attracts its armature and closes a circuit for relay 208 which in turn completes a circuit for driving sequence switch 220 out of position 17 and into position 1. The register sender has now been completely 55 restored to its normal position and may be taken in connection with the extension of subsequent calls.
- 56 The case will next be considered in which the calling subscriber having initiated a 60 call and obtained a register sender, is unable to complete the desired connection either because the sender fails to function properly or because he is unable to transmit impulses to the exchange. Upon the removal of his receiver from the hook and
- the extension of his line through to the first group selector, the relay 208 is energized in the manner above explained and sequence switch 220 advances into position 3. In the regular operation of the sender 70 the sequence switch 220 only remains in position 3 for a brief interval; being driven out of this position and into position 5 as soon as a series of impulses has been sent from the calling substation. In passing through position 2 sequence switch contact 219 closes a circuit for the right-hand winding of relay 222. Relay 222 attracts its armature and closes a locking circuit from battery over contact 231 of sequence switch 75 230 (closing in some position from 1 to 16), left-hand winding and armature and contact of relay 222 to ground at contact 221. On reaching position 3, sequence switch 220 closes a circuit from battery through the winding of relay 233, contact 218 (3), interrupter 232, to ground. On the first closure of the interrupter 232, relay 233 energizes and completes a circuit from battery through the winding of sequence switch 80 230, contact and armature and right-hand winding of relay 234 to ground at the front contact and armature of relay 233. A circuit is also closed in parallel thereto for the left-hand winding of relay 234. Relay 234 being differential does not operate since both of its windings are simultaneously energized. Sequence switch 230, however, advances 85 from the position in which it happens to be standing to the next succeeding position. When the master contact 247 closes, the right-hand winding of relay 234 is shunted out and this relay attracts its armature, thus opening the energizing circuit 90 of sequence switch 230. As soon thereafter as the interrupter 232 reaches an insulating segment relay 233 deenergizes and opens the circuit of the left-hand winding of relay 234, permitting this relay to release its armature. As the interrupter 232 reaches its 95 next conducting segment relay 233 energizes and sequence switch 230 is driven forward another position. This operation continues until sequence switch 230 moves from position 16 into position 1. On leaving position 16, contact 231 is opened and relay 222 deenergizes. Sequence switch 230 continues to advance until it reaches position 11 where a circuit is completed from battery over sequence switch contact 231 (11), left-hand winding of relay 223, back contact and armature of relay 222, contact 221 (3), to ground. Relay 223 attracts its armature and closes the following circuit: battery, over the left-hand armature and contact of relay 223, conductor 134, contact 135 (1) of sequence switch 130, left-hand winding of relay 113 to ground. Relay 113 energizes 100 and closes a circuit from ground over its 105

- 125
- 130

armature and front contact and contact 125 (1) for driving sequence switch 130 out of position 1 and into position 3. The brush carriage of the hunting switch 5 carrying the brushes 127, 128, 129, 131 and 132 is now rotated to advance its brushes over the terminal bank in search of the particular register sender that has been taken for use by a calling line and failed 10 to advance in the regular manner. The circuit for the power magnet 121, which controls the operation of the brush carriage, leads from battery through the winding of said magnet, contact 122 (3), back contact 15 and armature of relay 126 to ground at the front contact and armature of relay 113. When the hunting switch reaches the third set of terminals in its terminal bank, the brush 129 makes contact with terminal 240 20 and the following circuit is closed: ground over contact 117 (3), brush 129, terminal 240, conductor 136, contact 137 of key 105 at the operator's position, winding of relay 106, contact 138 of key 105, conductor 139, 25 contact 140 (3), resistance 141, to battery and ground. Relay 106 attracts its armature and completes a circuit from battery through the winding of sequence switch 120, contact and armature and left-hand winding 30 of relay 107 to ground at contact and armature of relay 106. In parallel to this circuit a circuit is closed from battery through the right-hand winding of relay 107 to ground at the contact and armature of relay 106. A circuit is also closed from battery through the winding of relay 108, contact and armature and left-hand winding of relay 107 to ground at contact and armature of relay 106. The relay 107 is 35 differential and therefore does not operate when both of its windings are energized. Sequence switch 120 energizes and passes from position 1 into position 2. Between positions 1 and 2 the master contact of sequence switch 120 short circuits the left-hand winding of relay 107, permitting this relay to energize. Relay 108 remains energized by means of a circuit closed by the master contact of sequence switch 120 until 40 said sequence switch reaches position 2. Relay 108 maintains an energizing circuit for the right-hand winding of relay 107, independent of the armature and contact of relay 106, to prevent the deenergization of relay 107 until sequence switch 120 has had time to advance into position 2. In the meantime the brush 129 of the hunting switch leaves terminal 240 and after sequence switch 120 has reached its second 45 position the relay 107 deenergizes.

When the hunting switch advances its brushes 127, 128, 129 and 131 onto the terminals 226, 227, 228 and 229, a circuit is closed from battery over the right-hand 50 armature and contact of relay 223, terminal trunk conductors 136 and 139. The depres-

229, brush 131, contact 118 (3), left-hand winding of relay 119 to ground. Relay 119 attracts its armature and closes a circuit through its right-hand winding and the winding of relay 126 to ground. Relay 126 70 becomes energized and opens the above-traced circuit for the power magnet 121, causing the hunting switch to come to rest. Relay 126 also closes a circuit from ground through the armature and front contact of relay 114, armature and front contact of relay 136, contact 124 (3), winding of sequence switch 130, to battery and ground. Sequence switch 130 energizes in this circuit and moves from position 3 into position 5. 75 In position 5 of sequence switch 130, relay 113 is maintained energized by means of a circuit from battery through the right-hand winding of said relay, contact 140 (5), conductor 139, contact 138 of key 105, relay 106, contact 137 of key 105, conductor 136, contact 135 (5), left-hand winding of relay 113 to ground. Relay 106 being marginal does not energize in series with the 80 windings of relay 113.

Since the register sender that has been associated with the operator's position is the first one appearing in the terminal bank of the hunting switch only one of the advance terminals, such as 240, is passed over by said switch. Consequently, the sequence switch 120 at the distant exchange has been advanced through one position only. Had the register sender seized by the hunting switch been the second, third or fourth 95 sender of the group, for example, the sequence switch 120 would have been advanced through 2, 3 or 4 positions respectively. At each deenergization of the relay 108 in the 100 advance of sequence switch 120, a momentary circuit is closed after said sequence switch reaches position 2 for the relay 109. The relay 109 is slow-to-energize and does not operate on short closures of its circuit. After relay 108 ceases to operate and 105 remains permanently deenergized, relay 109 attracts its armature and closes a circuit for the particular indicating lamp that has been selected by the sequence switch 120. In 110 the case assumed, the lamp 142 which designates the first sender of the group is lighted by means of a circuit from battery through said lamp, contact 143 (2) of sequence switch 120, contact and armature of relay 109 to ground. A signal lamp 111 is also 115 illuminated in a circuit closed at contact 110 as soon as sequence switch reaches position 2. The operator observing the lamp 111, knows that a sender is being associated with her position; also observing that the lamp 120 is lighted, she knows the designation of the particular sender involved. The operator thereupon depresses the key 105 which connects her telephone set to the 125 terminal trunk conductors 136 and 139. The depres-

sion of the key 105 also opens the circuit of relay 113. Relay 113 being deenergized closes a circuit from ground over its armature and back contact and contact 125 (5), 5 for driving sequence switch 130 out of position 5 and into position 7.

In this position a talking circuit is established between the calling subscriber's line and the operator's position. Talking battery 10 is supplied to the calling line over the windings of relay 114, sequence switch contacts 115 and 116, brushes 127 and 128, terminals 226 and 227, and conductors 202 and 203. The relay 204 is energized in the 15 seventh position of sequence switch 130 in a circuit from ground through the winding of said relay, terminal 128, brush 129, contact 117 (7), resistance 141, to battery and ground. The relay 204 disconnects the calling 20 subscriber's line from the winding of stepping relay 225 and connects the windings of said relay to the conductors 144 and 145 leading to the operator's position in the distant exchange. The operator converses 25 with the calling subscriber and obtains from him the number of the line with which he desires connection. Assuming that the calling subscriber is unable to transmit impulses to the exchange, the operator may then 30 manipulate her impulse sender 146, in accordance with the designation she receives from the calling party. The operation of the impulse sender 146 causes impulses to be sent to the stepping relay 225 of the selected 35 register sender. The circuit for the transmission of these impulses may be traced from battery through the left-hand winding of relay 225, front contact and left-hand armature of relay 204, conductor 145, contact 147 of key 105, impulse sender 146, contact 148 of key 105, conductor 144, right-hand armature and front contact of relay 40 204, right-hand winding of relay 225, back contact and right-hand armature of relay 45 249 to ground. After the register sender has thus been positioned by means of the operator's impulse sender, it proceeds in the regular manner to control the operation of the selective switches to establish the desired 50 connection between the calling and called lines. When the operator has completed the setting of the register sender she releases her key 105, which closes the above-traced circuit for relay 113 and relay 106. The 55 relay 113 energizes and completes a circuit from ground over its armature and front contact, contact 125 (7), winding of sequence switch 130, to battery and ground. The sequence switch 130 thereupon moves 60 out of position 7 and into position 9. In leaving position 7, contacts 135 and 140 are opened to permit the deenergization of relay 113. In position 9 of sequence switch 130 a circuit is established for the power magnet 121, traceable from battery through the

winding of said magnet, contact 122 (9), back contact and armature of relay 113, to ground. The brush carriage of the hunting switch commences to rotate. When the brush 129 engages the terminal 241 a circuit 70 is closed from ground over contact 117 (9), brush 129, terminal 241, conductor 136, contact 137 of key 105, winding of relay 106, contact 138 of key 105, conductor 139, contact 140 (9), resistance 141, to battery and 75 ground. The relay 106 energizes in this circuit and causes the advance of sequence switch 120 from position 2 into position 3 in the manner above explained. Upon the brush 129 engaging the terminal 248, relay 80 106 is again energized and sequence switch 120 moves to another position. Likewise for each set of terminals representing a register sender in the terminal bank of the hunting switch, the indicating switch 120 is moved 85 one position forward. The indicating switch 120 will be provided with as many positions as there are register senders represented in the terminal bank in the hunting switch so that when said hunting switch 90 is restored to its normal position, the switch 120 will also have reached its normal position. As the hunting switch restores to its normal position, the brush 131 engages the grounded contact 239. A circuit is then 95 closed from ground over said contact and brush, sequence switch contact 118 (9), right hand winding of relay 113, to battery and ground. Relay 113 energizes and opens the circuit of the power magnet 121, causing 100 the brush carriage of the hunting switch to cease to rotate. Relay 113 also closes a circuit from ground over its armature and front contact, contact 125 (9), winding of sequence switch 130 to battery 105 and ground. Sequence switch 130 moves from position 9 into position 1. The hunting switch and all apparatus connected therewith for associating the register senders with the operator's position has thus 110 been restored to its normal position. The timing mechanism shown within the broken rectangle at the lower left-hand corner of Fig. 2 is common to all register senders to which the hunting switch has access. As above explained, when any one of these register senders is connected to a calling line, sequence switch 220 immediately 115 passes into position 3. If impulses are sent to the register sender without delay the sequence switch 220 advances out of position 3 before the timing sequence switch 230 can reach position 11 to initiate the operation of the hunting switch. When sequence switch 220 remains in position 3 for a longer 120 period of time than required in its regular operation, the common timing apparatus 230 starts the hunting switch to search out the particular register sender while sequence switch 220 is standing in position 3 and as- 125 130

sociates the same with the operator's position.

What is claimed is:

1. In a telephone system, a subscriber's line, selective switches for extending said line, a plurality of register senders common to said switches for controlling the selective movement thereof, means for connecting the subscriber's line to one of said senders and for connecting the sender to one of said switches, an operator's position, and means common to said senders for automatically associating the particular sender to which said line is connected with the operator's position. 15
2. In a telephone system, a subscriber's line, selective switches for extending said line, a plurality of register senders common to said switches for controlling the selective movement thereof, means for connecting the subscriber's line to one of said senders and for connecting the sender to one of said switches, means controlled over said line for setting said sender, an operator's position, means common to said senders for automatically associating the particular sender to which said line is connected with the operator's position, and means controlled by the operator for setting said sender. 25
3. In a telephone system, a subscriber's line, selective switches for extending said line, a plurality of register senders common to said switches for controlling the selective movement thereof, means for connecting the subscriber's line to one of said senders and for connecting the sender to one of said switches, means for sending impulses over said line to register a desired designation on such sender, an operator's position, means common to said senders for automatically associating the particular sender to which said line is connected with the operator's position, and means controlled by the operator for registering designations on said sender. 35
4. In a telephone system, a subscriber's line, selective switches for extending said line, a plurality of register senders common to said switches for controlling the selective movement thereof, means for connecting the subscriber's line to one of said senders and for connecting the sender to one of said switches, an operator's position, and means common to said senders operative at the end of a definite interval after the connection of said line to one of said senders for associating such sender with the operator's position. 50
5. In a telephone system, a subscriber's line, selective switches for extending said line, a plurality of register senders common to said switches for controlling the selective movement thereof, means for connecting a subscriber's line to one of said
- senders and for connecting the sender to one of said switches, means controlled over said line for setting said sender, an operator's position, means common to said senders operative at the end of a definite 70 interval after the connection of said line to one of said senders for associating such sender with the operator's position, and means controlled from the operator's position for setting said sender to control said 75 switches.
6. In a telephone system, a subscriber's line, selective switches for extending said line, a plurality of register senders common to said switches for controlling the 80 selective movement thereof, means for connecting said line to one of said senders and for connecting the sender to one of said switches, an operator's position, and an automatically operated switch common 85 to said senders for associating the particular sender to which the subscriber's line is connected with the operator's position.
7. In a telephone system, a subscriber's line, an impulse transmitter in said line, 90 selective switches for extending said line, a plurality of register senders common to said switches for controlling the selective movement thereof, means for connecting said line to one of said senders and for 95 connecting the sender to one of said switches, means controlled by said impulse transmitter for setting said sender, an operator's position, an automatically operative switch common to said senders for 100 associating the particular sender to which the subscriber's line is connected with the operator's position, and means for sending impulses from the operator's position to set said sender. 105
8. In a telephone system, a subscriber's line, selective switches for extending said line, a plurality of register senders common to said selective switches, for controlling the selective movement thereof, means 110 for connecting said line to one of said senders and for connecting the sender to one of said switches, an operator's position, a hunting switch common to said senders, and means for automatically operating said 115 hunting switch at the end of a predetermined interval after the connection of said line with a register sender, said switch being arranged to select said sender and associate the same with the operator's position. 120
9. In a telephone system, a subscriber's line, selective switches for extending said line, a plurality of register senders common to said selector switches for controlling the selective movement thereof, means 125 for connecting said line to one of said senders and for connecting the sender to one of said switches, an operator's position, a hunting switch common to said senders, means for automatically operating said 130

- hunting switch at the end of a predetermined interval after the connection of said line to the register sender, said switch being arranged to select said sender and associate the same with the operator's position, and impulse-sending means at the operator's position for setting said sender in accordance with a desired designation. 10. In a telephone system, a subscriber's line, selective switches for extending said line, a plurality of register senders common to said switches for controlling the selective movement thereof, means for connecting said line to one of said senders and for connecting the sender to one of said switches, an operator's position, a hunting switch common to said senders, a timing device arranged to operate in cycles, and means controlled by said device at the end 20 of its cycle for starting said hunting switch, said switch being arranged to select the particular sender to which said line is connected and associate the same with the operator's position. 11. In a telephone system, a subscriber's line, selective switches for extending said line, a plurality of register senders common to said switches for controlling the selective movement thereof, means for connecting said line to one of said senders and for connecting the sender to one of said switches, an operator's position, a hunting switch common to said senders, a timing device arranged to operate in cycles, means 30 for initiating the operation of said device when said line is connected to one of said senders, and means operated by said device at the end of its cycle for starting said hunting switch, said hunting switch being arranged to select the particular sender to which the subscriber's line is connected and associate the same with the operator's position. 12. In a telephone system, a subscriber's line, selective switches for extending said line, a plurality of register senders common to said switches for controlling the selective movement thereof, means for connecting said line to one of said senders and for connecting the sender to one of said switches, means under the control of the subscriber for setting such sender, an operator's position, a hunting switch common to said senders, a timing device arranged 40 to operate in cycles, means for initiating the operation of said device when said line is connected with one of said senders, means operated by said device at the end of its cycle for starting said hunting switch, said hunting switch being arranged to select the particular sender to which the subscriber's line is connected and associate the same with the operator's position, and means for placing the setting of said sender under the control of the operator. 13. In a telephone system, a subscriber's line, selective switches for extending said line, a plurality of register senders common to said switches for controlling the selective movement thereof, means for connecting said line to one of said senders and for connecting the sender to one of said switches, an operator's position, switching means common to said senders for automatically associating the particular sender to which said line is connected with the operator's position, and circuits controlled by said switching means for establishing a talking connection between said subscriber's line and the operator's position. 14. In a telephone system, a subscriber's line, selective switches for extending said line, a plurality of register senders common to said switches for controlling the selective movement thereof, means for connecting said line to one of said senders and for connecting the sender to one of said switches, means controlled from the substation of said line for setting said sender, an operator's position, switching means common to said senders for automatically associating the particular sender to which said line is connected with the operator's position, circuits controlled by said switching means for establishing a talking connection between said subscriber's line and the operator's position, and means controlled from the operator's position for setting said sender. 15. In a telephone system, a subscriber's line, selective switches for extending said line, a plurality of register senders common to said switches for controlling the selective movement thereof, means for connecting the subscriber's line to one of said senders and for connecting the sender to one of said switches, an operator's position, a hunting switch common to said senders, means operative at the end of a given time interval after the connection of said line to one of said senders for starting said hunting switch, said hunting switch being arranged to associate such sender with the operator's position, and circuits controlled by said hunting switch for establishing a talking connection between said subscriber's line and the operator's position. 16. In a telephone system, a subscriber's line, selective switches for extending said line, a plurality of register senders for controlling said switches, means for connecting said line to one of said senders, an operator's position, means common to said senders for automatically associating the particular sender to which said line is connected with the operator's position, and an indicating device for indicating to the operator the designation of the sender that has been associated with her position. 17. In a telephone system, a subscriber's

line, selective switches for extending said line, a plurality of register senders for controlling said switches, means for connecting said line to one of said senders, an operator's position, means common to said senders for automatically associating the particular sender to which said line is connected with the operator's position, and a selectively operable indicating device for indicating to the operator the designation of the sender that has been associated with her position.

18. In a telephone system, a subscriber's line, selective switches for extending said line, a plurality of register senders for controlling said switches, means for connecting said line with one of said senders, an operator's position, an automatic switch common to said senders, means for operating said automatic switch to select the particular sender to which the subscriber's line is connected and associate the same with the operator's position, a plurality of indicating devices, and a selective switch for selecting said devices to indicate to the operator the designation of said senders, said last-named switch being arranged to advance automatically in response to the operation of said automatic switch.

19. In a telephone system, a subscriber's line, selective switches for extending said line, a plurality of register senders common to said switches for controlling the selective movement thereof, means for connecting the subscriber's line to one of said senders and for connecting the sender to one of said switches, an operator's position, and means operative at the end of a definite interval after the connection of said line to one of said senders for associating said line with the operator's position.

20. In a telephone system, a subscriber's line, selective switches for extending said

line, a plurality of register senders common to said switches for controlling the selective movement thereof, means for connecting the subscriber's line to one of said senders and for connecting the sender to one of said switches, means controlled over said line for setting said sender, an operator's position, and means operative at the end of a definite interval after the connection of said line to one of said senders for associating said line with the operator's position.

21. In a telephone system, a subscriber's line, selective switches for extending said line, a plurality of register senders common to said switches for controlling the selective movement thereof, means for connecting the subscriber's line to one of said senders and for connecting the sender to one of said switches, an operator's position, means operative at the end of a definite interval after the connection of said line to one of said senders for associating said line with the operator's position, and means for indicating to the operator that a line has become associated with her position.

22. In a telephone system, a subscriber's line, selective switches for extending said line, a plurality of register senders common to said switches for controlling the selective movement thereof, means for connecting the subscriber's line to one of said senders and for connecting the sender to one of said switches, an operator's position, and automatic switching means operative at the end of a definite interval after the connection of said line to one of said senders for associating said line with the operator's position.

In witness whereof, I hereunto subscribe my name this 13th day of October A. D., 1919.

LIPA POLINKOWSKY.
